DOWEL ROD ANCHOR

Samuel J. Crockett, Philippi, W. Va.

Application July 11, 1952, Serial No. 298,390

20 Claims. (Cl. 61—45)

1

My invention relates to improvements in means for safely supporting the roof of an underground mine or other tunnel; and in particular relates to an improved means for anchoring the inner ends of dowel rods within bores drilled in the roof of the mine, which bores may be drilled by any conventional method.

The recent trend in securing the roofs of certain types of mines against cave-ins has been to drill bores diagonally upwardly into the strata above the roof of the mine, and to drive a snugly-fitting dowel rod into the bore, the rod having an automatic anchoring means at its inner end, which means is actuated when the dowel arrives at the blind end of the bore. The dowel rod furnishes a certain degree of vertical support to the rock strata above the roof but is primarily intended to prevent lateral shifting of the strata resulting from vibrations set up in the mine while it is being worked. Such lateral shifting breaks the natural bond between the various superjacent strata in the mine roof, and causes cave-ins. By driving the dowel rods into the afore-mentioned bores, the rock strata are pinned together to prevent such lateral shifting.

Until recently, the practice of the industry has been to use metal pins within the bores, such pins being, however, relatively expensive to purchase and being wasteful of valuable metal since these pins usually cannot be removed from the bores when the mine tunnel is to be abandoned. Therefore, the present trend has been toward the use of wooden dowel rods, and the present invention is intended to provide an inexpensive and efficient anchor for the inner ends of said rods.

The primary object of my invention is to provide an efficient and reliable anchoring means providing a double-acting wedge action, said anchor consisting of a center wedge adapted to force a plurality of adjacent slip members outwardly to engage the sides of the bore, the slip members being located in slots having "reversed" or upwardly narrowing tapers which cause the slips to forcibly spread the upper end of the dowel rod to further tighten the engagement thereof with the bore.

Another important object of my invention is to provide a trip means associated with the center wedge of the anchor, which trip means is actuated by abutting the blind end of the bore to drive the wedge downwardly and cause lateral spreading of the slips and engagement thereof with the walls of the bore.

Still another object of my invention is to pro-

2

vide the bore-engaging surfaces of the slip members with transverse striations to assist in gripping the walls of the bore and also to undercut the lower ends of said members so as to leave downwardly projecting teeth at the bottom ends thereof, said teeth tending to dig into the bore walls and prevent further downward motion of the slips when the dowel is partially retracted outwardly with respect to the bore.

10 Another very important object of my invention is to provide an anchor means of the character specified which eliminates the necessity of hammering the dowel violently from below to cause setting of the anchor, such hammering tending to cause injury to the rod, as well as having a tendency to loosen the strata in the mine roof, and thereby contribute to a subsequent cave-in.

The present dowel rod may be provided with a bearing plate at its lower end which is screwed 20 to said lower end after the dowel rod is in place in the bore, the tightening of said screw means causing retraction of the dowel rod for a distance sufficient to drive the slip members tightly into the "reversed" taper, thereby spreading the 25 inner end of the dowel rod into tight engagement with the inner walls of the bore.

Other objects and advantages of my invention will become apparent during the following discussion of the drawings, wherein:

30 Figure 1 is a section through the roof of a mine, showing one of my dowel rods secured in place.

Fig. 2 is a section view taken along line 2—2, Fig. 1, and somewhat enlarged.

35 Fig. 3 is a section view taken along line 3—3, Fig. 1, and somewhat enlarged.

Fig. 4 is a perspective view showing the inner wedge and associated trip means and showing the two outer slip members there adjacent.

40 Referring to the drawings, above the roof R of the mine are rock strata S frequently comprising relatively large slabs. As shown in Fig. 1, the lowermost stratum is sometimes draw slate D which has a tendency to crumble and fall. A bore H is drilled upwardly into the strata S and receives the dowel rod 1, the latter having, in the illustrated embodiment, a bifurcated inner end dividing the end into portions 1a and 1b. The outer end of the dowel is provided with an axial bore 1c for the purpose hereinafter set forth.

45 As shown in Fig. 1, the bifurcated upper portions 1a and 1b define a slot having an upper narrow portion 1d and tapering downwardly and 50 outwardly along a portion 1e, to form the afore-

mentioned "reversed" wedge, the tapered portion $1e$ normally housing two slip members 2 separated by a wedge 3 . The lower ends of the tapered portion of the slot $1e$ are provided with footings $1f$ so that before the anchor is expanded and set, the lower ends $2a$ of the slip members 2 rest against the footings $1f$, the slips 2 fitting snugly within the tapered walls $1e$ of the slot, and the bore-engaging edges $2b$ of the slips being flush with the outer periphery of the dowel rod 1 .

As shown in Figs. 2 and 4, the inner surfaces $2c$ of the slip members 2 are upwardly and outwardly tapered at an angle which is complementary to the tapered surfaces $3a$ of the wedge 3 . When the anchor is in its initial or unset position, the lower end $3b$ of the wedge 3 is even with the lower ends $2a$ of the members 2 , and the trip bar 4 extends upwardly beyond the upper end of the dowel rod 1 . But as the dowel rod is driven upwardly into the bore H , the upper end of the trip 4 abuts against the blind end of the bore H so that upon further insertion of the dowel rod 1 into the bore H , the wedge 3 is pressed downwardly with respect to the members 2 by the trip 4 and the surfaces $3a$ of the wedge 3 press against the complementary surfaces $2c$ of the slip members 2 and cause said members to spread laterally outwardly with respect to the outer periphery of the dowel rod 1 and engage the walls of the bore H .

The outer lower ends of the slips 2 are undercut as at $2d$ so as to provide toothlike portions $2e$ which dig into the walls of the bore H and prevent downward motion on the part of the members 2 with respect to said walls. The outer bore-engaging surfaces $2b$ of the members 2 are further provided with a plurality of striations $2f$ to secure a better grip on the walls of the bore H .

Note in Fig. 2 that the dowel rod 1 is also provided with an additional slot $1g$ extending downwardly from the tapered slot $1e$ and adapted to provide clearance for the lower end of the wedge 3 when the latter is pressed downwardly to expand the slips 2 as the anchor is set in the bore.

At the lower end of the dowel rod 1 is a bearing plate 5 having a hole $5a$ therethrough, Fig. 1. A screw 6 extends upwardly through the hole $5a$ and into the bore $1c$, the bore $1c$ having been drilled to the root diameter of the threads on the screw 6 so as to provide a strong grip when the screw is tightened therein.

In addition, a collar 7 is provided around the lower end of the dowel 1 so as to counteract any tendency that the screw may have to split the lower end of the dowel. This bearing plate 5 may be any desired shape and is provided for the purpose hereinafter described.

The device is used as follows:

The bore H is first drilled upwardly into the rock strata S and is slightly longer than the length of the dowel rod 1 . The slips 2 are placed snugly within the slot portion $1e$ so that they will not fall out, and the wedge 3 is placed between the slips 2 with the bottom end $3b$ of the wedge approximately even with the bottoms $2a$ of the slips 2 , so that in this position the outer surfaces $2b$ of the slips 2 are flush with the outer periphery of the dowel rod 1 , the trip 4 extending upwardly well above the inner end of the dowel rod 1 . When the dowel rod is inserted in the bore H , the trip 4 abuts the blind end of the bore H , and the outer end of the dowel rod 1 is tapped upwardly from below so as to drive the trip 4 and the wedge 3 downwardly with respect to the slips 2 , thereby spreading the latter outwardly and

digging them tightly into the walls of the bore H .

The bearing plate 5 is then placed against the roof of the mine, and the screw 6 is passed through the hole $5a$ and is screwed tightly into the bore $1c$, thereby causing a slight retraction of the dowel rod within the bore H . Since the slips 2 have dug into the walls of the bore H and the teeth $2e$ are tightly secured therein to prevent shifting of the slips longitudinally of the bore H , upon the slight retraction of the dowel rod 1 caused by the tightening of the screw 6 the tapered walls $1e$ of the slot will move downwardly with respect to the slips 2 so that the bifurcated ends $1a, 1b$ of the dowel rod will be forced to spread outwardly, thereby providing additional anchoring of the inner end of the dowel rod 1 , the retraction of the dowel rod 1 with respect to the bore being only over a relatively short distance X , Fig. 2. The plate 5 also serves to provide some vertical support for the draw slate layer D .

As stated in the objects of this invention, the above assembly, because of the "reversed" wedge, provides an anchoring action which is augmented by any downward movement of the dowel rod 1 with respect to the slips 2 so that the greater the downward pull on the dowel rod, the tighter the anchor is set within the upper end of the bore H .

I do not limit my invention to the exact form shown in the drawings, for obviously changes may be made therein within the scope of the claims.

I claim:

1. A strata dowel to be anchored in a blind-end bore in the roof of a mine for securing together the strata thereabove, comprising a rod substantially the diameter of said bore, said rod being bifurcated at its upper end by a slot extending axially therewith, the slot being tapered to converge upwardly; a pair of complementarily tapered slips in said slot, the slips being spaced apart and having inner adjacent surfaces tapering to diverge upwardly; a wedge between said slips having a taper complementary to that of said inner adjacent surfaces; and an elongated trip bar fixed to the top of said wedge and extending upwardly out of said slot and beyond the end of said rod, whereby as said rod is pushed into said bore the trip bar will bottom on said blind end and force said wedge downwardly with respect to said slips thereby expanding the slips laterally outwardly to embed them in the walls of the bore so that a downward pull on said rod will cause said slips to wedge deeper into the taper of said slot and expand said bifurcated upper end.

2. In a device as set forth in claim 1, said slips each having an outer bore-engaging surface having striations thereon to tightly grip the walls of said bore, and the lower end of said slips each being undercut to leave tooth-like projections to prevent shifting of said slips axially of said bore.

3. In a device as set forth in claim 1, said bore being deeper than the length of said rod, and said rod having a second bore in its lower end; a bearing plate having a hole therethrough, and a screw adapted to transfix said hole and said second bore, whereby when said rod is inserted in said first bore with its lower end above the roof of the mine and said screw is tightened, the rod will be forcibly moved downwardly in said first bore to wedge said slips.

4. A strata dowel to be anchored in a blind-end bore in the roof of a mine for securing to-

gether the strata thereabove, comprising a rod substantially the diameter of said bore, said rod being bifurcated at its upper end by a slot extending axially thereinto, the slot being tapered to converge upwardly; a pair of complementarily tapered slips in said slot, the slips being spaced apart and having inner adjacent surfaces tapering to diverge upwardly; a wedge between said slips having a taper complementary to that of said inner adjacent surfaces and said wedge extending upwardly out of said slot and beyond the end of said rod, whereby as said rod is pushed into said bore the wedge will bottom on said blind end and be forced downwardly with respect to said slips thereby expanding the slips laterally outwardly to embed them in the walls of the bore so that a downward pull on said rod will cause said slips to wedge deeper into the taper of said slot and expand said bifurcated upper end.

5. In a device as set forth in claim 4, said slips each having an outer bore-engaging surface having striations thereon to tightly grip the walls of said bore, and the lower end of said slips each being undercut to leave tooth-like projections to prevent shifting of said slips axially of said bore.

6. In a device as set forth in claim 4, said bore being deeper than the length of said rod, and said rod having a second bore in its lower end; a bearing plate having a hole therethrough, and a screw adapted to transfix said hole and said second bore, whereby when said rod is inserted in said first bore with its lower end above the roof of the mine and said screw is tightened, the rod will be forcibly moved downwardly in said first bore to wedge said slips.

7. A strata dowel to be anchored in a blind-end bore in the roof of a mine for securing together the strata thereabove, comprising a rod substantially the diameter of said bore, said rod having at its upper end a slot extending axially thereinto, the slot being tapered to converge upwardly; a pair of complementarily tapered slips in said slot, the slips being spaced apart and having inner adjacent surfaces tapering to diverge upwardly; a wedge between said slips having a taper complementary to that of said inner adjacent surface and said wedge extending upwardly out of said slot and beyond the end of said rod, whereby as said rod is pushed into said bore the wedge will bottom on said blind end and be forced downwardly with respect to said slips thereby expanding the slips laterally outwardly to embed them in the walls of the bore so that a downward pull on said rod will cause said slips to wedge deeper into the taper of said slot and expand the upper end of the rod.

8. In a device as set forth in claim 7, said slips each having an outer bore-engaging surface having striations thereon to tightly grip the walls of said bore, and the lower end of said slips each being undercut to leave tooth-like projections to prevent shifting of said slips axially of said bore.

9. In a device as set forth in claim 7, said bore being deeper than the length of said rod, and said rod having a second bore in its lower end; a bearing plate having a hole therethrough, and a screw adapted to transfix said hole and said second bore, whereby when said rod is inserted in said first bore with its lower end above the roof of the mine and said screw is tightened, the rod will be forcibly moved downwardly in said first bore to wedge said slips.

10. A strata dowel to be anchored in a blind-

end bore in the roof of a mine for securing together the strata thereabove, comprising a rod substantially the diameter of said bore, said rod having a concentric bore in its upper end and slots through its upper end communicating with said second bore, each slot being tapered to converge upwardly; a complementarily tapered slip in each slot, the slips being spaced from the axis of said second bore and having inner adjacent surfaces tapering to diverge upwardly; a wedge in said second bore having tapered surfaces complementary to said inner adjacent surfaces and said wedge extending upwardly out of said second bore and beyond the end of said rod, whereby as said rod is pushed into said first bore the wedge will bottom on said blind end and be forced downwardly with respect to said slips thereby expanding the slips laterally outwardly to embed them in the walls of the first bore so that a downward pull on said rod will cause said slips to wedge deeper into the tapers of said slots and expand said upper end.

11. In a device as set forth in claim 10, said slips each having an outer bore-engaging surface having striations thereon to tightly grip the walls of said first bore, and the lower end of said slips each being undercut to leave tooth-like projections to prevent shifting of said slips axially of said first bore.

12. In a device as set forth in claim 10, said first bore being deeper than the length of said rod, and said rod having a screw hole in its lower end; a bearing plate having a hole therethrough, and a screw adapted to transfix said holes, whereby when said rod is inserted in said first bore with its lower end above the roof of the mine and said screw is tightened, the rod will be forcibly moved downwardly in said first bore to wedge said slips.

13. An anchor for securing a rod in a complementary bore having a blind end, comprising a rod bifurcated at its inner end by a slot extending axially thereinto, the slot being tapered to converge toward its open end; a pair of complementarily tapered slips in said slot, the slips being spaced apart and having inner adjacent surfaces tapered to diverge toward the open end of the slot; a wedge between said slips having a taper complementary to that of said inner adjacent surfaces; and an elongated trip bar fixed to said wedge and extending outwardly through the open end of the slot beyond the end of the rod, whereby as said rod is pushed into said bore the trip bar will bottom on said blind end and force said wedge between said slips thereby expanding the latter outwardly to embed them in the walls of said bore so that any subsequent outward motion of said rod with respect to said bore will cause said slips to wedge deeper into the taper of said slot and expand said bifurcated inner end.

14. In a device as set forth in claim 13, said slips each having an outer bore-engaging surface having striations thereon to tightly grip the walls of said bore, and the ends of said slips opposite from the open end of the slot being undercut to leave tooth-like projections to prevent shifting of said slips axially of said bore.

15. An anchor for securing a rod in a complementary bore having a blind end, comprising a rod bifurcated at its inner end by a slot extending axially thereinto, the slot being tapered to converge toward its open end; a pair of complementarily tapered slips in said slot, the slips being spaced apart and having inner adjacent

surfaces tapered to diverge toward the open end of the slot; a wedge between said slips having a taper complementary to that of said inner adjacent surfaces and said wedge extending outwardly through the open end of the slot beyond the end of the rod, whereby as said rod is pushed into said bore the wedge will bottom on said blind end and be forced between said slips thereby expanding the latter outwardly to embed them in the walls of said bore so that any subsequent outward motion of said rod with respect to said bore will cause said slips to wedge deeper into the taper of said slot and expand said bifurcated inner end.

16. In a device as set forth in claim 15, said slips each having an outer bore-engaging surface having striations thereon to tightly grip the walls of said bore, and the ends of said slips opposite from the open end of the slot being undercut to leave tooth-like projections to prevent shifting of said slips axially of said bore. 15

17. An anchor for securing a rod in a complementary bore having a blind end, comprising a rod having a slot extending axially into its inner end, the slot being tapered to converge toward its open end; a pair of complementarily tapered slips in said slot, the slips having inner adjacent surfaces tapered to diverge toward the open end of the slot; a wedge between said slips having a taper complementary to that of said inner adjacent surfaces and said wedge extending outwardly through the open end of the slot beyond the end of the rod, whereby as said rod is pushed into said bore the wedge will bottom on said blind end and be forced between said slips thereby expanding the latter outwardly to embed them in the walls of said bore so that any subsequent outward motion of said rod with respect to said bore will cause said slips to wedge deeper into the taper of said slot and expand the inner 40 end of the rod. 20

18. In a device as set forth in claim 17, said slips each having an outer bore bore-engaging surface having striations thereon to tightly grip the walls of said bore, and the ends of said slips opposite from the open end of the slot being undercut to leave tooth-like projections to prevent shifting of said slips axially of said bore. 5

19. An anchor for securing a rod in a complementary bore having a blind end, comprising a rod having a concentric bore in its inner end and slots through its inner end communicating with said second bore, the slots being tapered to converge toward said inner end; a complementarily tapered slip in each slot, the slips being spaced from the axis of said second bore and having inner adjacent surfaces tapered to diverge toward the inner end of the rod; a wedge in said second bore having tapered surfaces complementary to said inner adjacent surfaces and said wedge extending outwardly beyond the inner end of the rod, whereby as said rod is pushed into said first bore the wedge will bottom on said blind end and be forced between said slips thereby expanding the latter outwardly to embed them in the walls of said first bore so that any subsequent outward motion of said rod with respect to said first bore will cause said slips to wedge deeper into the tapers of said slots and expand said inner end. 25

20. In a device as set forth in claim 19, said slips each having an outer bore-engaging surface having striations thereon to tightly grip the walls of said first bore, and the ends of said slips opposite from the open ends of the slots being undercut to leave tooth-like projections to prevent shifting of said slips axially of said first bore. 30
